UNITED STATES PATENT OFFICE.

CECIL T. NEIL, OF LEAD, SOUTH DAKOTA.

NURSING-BOTTLE HOLDER.

1,292,631.

Specification of Letters Patent. Patented Jan. 28, 1919.

Application filed March 15, 1918. Serial No. 222,654.

To all whom it may concern:

Be it known that I, CECIL T. NEIL, a citizen of the United States, residing at Lead, in the county of Lawrence and State of South Dakota, have invented certain new and useful Improvements in Nursing-Bottle Holders, of which the following is a specification.

The invention relates to artificial feeding of infants, and more particularly to means for holding a bottle or like container in proper position so that the contents thereof may be obtained without permitting air to be taken along with the food and which is the chief source of producing colic and like infantile ailments.

The invention has for its main purpose to provide supporting means for a bottle or kindred article whereby the same may be adjusted to vary the height and inclination to suit the position and comfort of the infant, thereby obviating inconvenience and failure to properly obtain nourishment which causes produce fretting of the infant, thereby adding materially to the care required to be exercised in the proper nursing.

The drawing illustrates a preferred embodiment of the invention, however, it is to be understood that in adapting the same to meet different conditions, various changes in the form, proportion, and minor details of construction may be resorted to without departing from the nature of the invention as claimed hereinafter.

35 In the drawings:—

Figure 1 is a view in elevation of means embodying the invention for supporting a nursing bottle or like article.

Fig. 2 is a top plan view of the parts shown in Fig. 1.

Fig. 3 is a perspective view of the holder.

Fig. 4 is a perspective view of a modification.

45 Corresponding and like parts are referred to in the following description and indicated in the several views of the drawings by like reference characters.

The holder is designated generally by the reference letter A, the same being supported by sustaining means B.

50 The holder comprises two similar or like plates 1 which are oblong and may be rectangular as illustrated in Fig. 3 of the drawings, or oval as shown in Fig. 4. The plates 1 are connected by means of suitable fasten-

ings 2 which are indicated as bolts provided with thumb nuts 3 whereby provision is had for adjusting the plates so as to grip the bottle or like container therebetween. The fastening means 2 may also serve as holding means to prevent vertical or lateral displacement of the bottle, as indicated most clearly in Fig. 1. The plates 1 may be of any suitable material and are of light construction so as to avoid a cumbersome appearance. In the event of the plates 1 consisting of sheet metal, it will be readily understood that they will be sufficiently resilient or pliable to conform to the sides of the bottle so as to grip the same without causing fracture or other injury. Should the plates 1 be formed of sheet metal it will be necessary to fold or wire the edges in order to prevent sharp edges which would be likely to produce injury. This folding or wiring of the edges of the plates will also serve to properly stiffen the same.

The sustaining means B may be of wire or material of any nature. The inner ends of the sustaining means are attached to the plates of the holder; whereas their outer ends are designed to be attached to the crib, carriage, or other supporting means in any convenient and determinate way. By proper adjustment of the sustaining means, it will be readily understood that the position of the bottle may be adjusted to best meet the requirements of the infant to be fed so as to insure nourishment being obtained without wind passing into the stomach along with the food. As indicated, studs 4 project laterally from opposite sides of the holder, and the inner ends of the sustaining means B are attached thereto. One or both of the studs 4 may be adjustable to admit of varying the inclination of the holder. For this purpose, one or both of the studs 4 may be attached to a longitudinally slotted plate 5 which is adjustably secured to the holder by means of a threaded element 6, and a winged nut 7 coöperating therewith. This arrangement admits of the stud 4 being adjusted vertically and laterally so as to secure various positions of the holder according to the requirements of the infant to be fed. 105

In accordance with the invention the bottle or like article containing the food is placed between the plates or gripping elements 1 of the holder A and is made secure by tightening the nuts 3. The holder is 110

properly sustained by the means B after which the holder may be adjusted by proper manipulation of the plate or like member 5 in the manner stated. This insures the proper positioning of the nursing bottle so that the infant may obtain all the food without drawing wind into the stomach and without becoming fretted as is frequently the case when the bottle becomes displaced before the contents are drawn therefrom.

What I claim is:

1. A nursing bottle holder, studs at opposite sides of the holder and relatively adjustable in every direction, means for secur-

ing the studs in the adjusted position, and suspending means engaging the studs.

2. A nursing bottle holder, members at opposite sides of the holder and adjustable vertically and angularly, means for securing the members in the adjusted position, and suspending means engaging an end of the adjustable members.

In testimony whereof I affix my signature in presence of two witnesses.

CECIL T. NEIL.
